US00D986514S

(12) **United States Design Patent** (10) **Patent No.:** **US D986,514 S**
(45) **Date of Patent:** **** May 16, 2023**

(54) **PET LEAD**

(71) Applicant: **Quan Xu**, Hubei (CN)

(72) Inventor: **Quan Xu**, Hubei (CN)

(**) Term: **15 Years**

(21) Appl. No.: **29/886,247**

(22) Filed: **Mar. 7, 2023**

(51) **LOC (14) Cl.** **30-04**

(52) **U.S. Cl.**

USPC **D30/153**

(58) **Field of Classification Search**

USPC D30/144-145, 151-153, 160, 199;
D10/72; D26/38

CPC A01K 27/00; A01K 27/003; A01K 27/004

See application file for complete search history.

(57) **CLAIM**

The ornamental design for a pet lead, as shown and described.

DESCRIPTION

FIG. 1 is a front, right and top perspective view of a pet lead, showing my design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof; and,

FIG. 8 is a bottom plan view thereof.

The broken lines depict portions of the pet lead that form no part of the claimed design.

1 Claim, 8 Drawing Sheets
